UNITED STATES PATENT OFFICE.

ELI ISRAEL, OF WILKES-BARRE, PENNSYLVANIA.

LAMP HOLDER FOR MINERS' CAPS.

Application filed February 24, 1922. Serial No. 538,983.

To all whom it may concern:

Be it known that I, ELI ISRAEL, a citizen of the United States, residing at Wilkes-Barre, in the county of Luzerne and State 5 of Pennsylvania, have invented certain new and useful Improvements in Lamp Holders for Miners' Caps, of which the following is a specification.

This invention relates to improvements in 10 lamp holders for miners' caps and has as its general object to provide a device for this purpose which will possess many advantages not present in holders of the ordinary construction and which will furthermore over- 15 come many of the disadvantages which attend the use of the ordinary types of holders.

Miners' lamps are ordinarily provided upon their rear sides with a hooked stem, and the miner's cap is usually provided with 20 an opening in the holder through which the stem is to be fitted, and the lamp thus supported upon the front of the cap. However the bill of the hooked stem, in such a construction, projects into the cap and, should 25 the miner strike his head against an overhead beam or other object, there is liability of the point of the hooked stem cutting a gash in his forehead. Therefore it is one of the primary objects of the present invention 30 to provide a holder so constructed that the stem of the lamp, when engaged therewith, will be located wholly exteriorly of the cap so that such an accident cannot occur.

Another object presented by the ordinary 35 holder is that when the head is inclined forwardly, the stem of the lamp is liable to slip from engagement with the holder thus permitting the lamp to fall to the ground. It is therefore a further object of the invention 40 to so construct the holder as to overcome this disadvantage and insure against dropping of the lamp.

The ordinary type of holder is also objectionable for the reason that the lamp is permitted to have more or less side play, and therefore the invention has as a further important object to so construct the holder that when the stem of the lamp is engaged therewith the lamp will be firmly held 50 against any lateral swinging movement and will consequently at all times be presented directly forwardly with relation to the cap.

Also in the ordinary types of holders the opening or socket into which the stem of the lamp is to be fitted is of substantially uniform diameter and a miner will experience

difficulty in inserting the stem into the said opening or socket in replacing the lamp after it has been removed for any purpose such for example as lighting or refilling it, 60 and therefore the invention further contemplates so forming the stem receiving socket as to permit of a more ready and convenient insertion of the stem therein.

In the accompanying drawings: 65

Figure 1 is a perspective view of the device embodying the invention in use;

Figure 2 is a vertical front to rear sectional view through the device, the lamp being shown in elevation; 70

Figure 3 is a perspective view of the socket member comprising the device removed from the cap; and

Figure 4 is a front elevation of the socket member applied to the cap, the lamp stem 75 being shown in section.

In the drawings the numeral 1 indicates in general an ordinary miners's cap comprising the usual crown 2 and visor 3. To the front of the cap there is applied, exteriorly, a supporting base member which is indicated in general by the numeral 4 and which may comprise a sheet of stiff leather or a sheet of metal or other material suitable for the purpose, this sheet having a portion 5 disposed vertically in front of the crown 2, an upper end portion 6 which extends rearwardly from the upper end of the portion 5 and is riveted or otherwise secured as at 7 to the top of the crown 2, and a lower end portion 8 which extends downwardly and forwardly along the upper side of the visor 3 and is secured by rivets or the like indicated by the numeral 9. 80

The lamp is indicated in general by the 85 numeral 10 and may be any of the well known types, in the present illustration an acetylene lamp, and this lamp is provided upon its rear side, as is usual, with an attaching stem 11 which has the general form 90

of a hook and includes a bight portion 12 and a bill 13 which latter extends downwardly in spaced relation to the rear side of the lamp. The shank of this hooked stem is indicated by the numeral 14 and is 105 suitably spaced from the bill 13 and secured in any suitable manner to the lamp 10.

The supporting device embodying the invention is indicated in general by the 110 numeral 15 and the same comprises, preferably, a one piece casting including a back plate 16 provided at its upper edge with a

rearwardly directed ear 17. The end portions of the back plate 16 are provided with openings 18, and a similar opening 19 is provided in the ear 17. In assembling the supporting member with the base member 4, the back plate 16 is disposed against the forward side of the portion 5 of the said base member with the ear 17 projecting over and in contact with the upper side of the portion 6 of the base member, and rivets or the like indicated by the numeral 20 are secured through the openings 18 and 19 and through the said portions of the base member 4. A boss 21 is provided upon the forward side 15 of the back plate 16 and is of substantially rectangular form and provided, near its juncture with the back plate, with a vertically extending socket 22 which is flared at its upper end as indicated by the numeral 23 and gradually tapered in the direction 20 of its lower end where it is of substantially the same diameter as the bill of the stem 11. A groove 24 is formed in the upper side of the boss 21 and merges at its rear end into the flared upper end 23 of the socket 22 and at its forward end merges into the upper end of a groove 25 which is formed vertically in the forward side of the said boss.

In mounting the lamp upon the supporting device embodying the invention, the bill 13 of the hooked stem 11 is inserted into the socket 22 through the flared upper end 23 of said socket, being guided into place by the downwardly converging walls of the socket and will finally come to rest in substantially the position shown in Figure 2 of the drawings in which position it will project through the lower end of the socket and engage at its extremity against the forward side of the portion 5 of the base member 4. The bight 12 of the hooked stem will engage in the groove 24, seating more or less snugly between the side walls of said groove, and in like manner the shank 14 of the stem will engage in the upper portion of the groove 25 and seat between the side walls of said groove. Thus the stem will be so engaged as to preclude any pivotal or swinging movement with relation to the supporting member, and consequently the

lamp will be rigidly supported and maintained in a forwardly presented position. At the same time the lamp may be readily removed from the supporting or holding means whenever occasion requires and may 55 equally as readily be replaced. Due to the relatively snug fit of the bill of the hooked stem 11 in the lower end of the socket 22 and the engagement of its extremity against the forward side of the portion 5 of the base 60 member 4, there will be no likelihood of the lamp being dropped in the event the wearer's head is inclined forwardly.

Another advantage possessed by the holding device embodying the invention lies in 65 the fact that the lamp is supported in position spaced a considerable distance from the crown of the cap so that air may freely circulate between the lamp and cap and little or no heat will be transmitted to the 70 head of the wearer.

Having thus described the invention what is claimed as new is:

As a new article of manufacture, a supporting member for attachment to a miner's 75 cap for supporting a miner's lamp by the usual stem of said lamp, comprising an attaching plate having terminal portions apertured for the passage of securing elements and provided with a boss upon its 80 face located between said apertures, the boss being provided with a vertically extending socket substantially adjacent its juncture with the plate, the socket being flared at its upper end and being closed on all sides 85 except at its upper and lower ends, the upper and forward sides of the boss being formed with grooves, the upper end of the groove in the forward side of the boss and the forward end of the groove in 90 the upper side of the boss merging with each other, and the rear end of the groove in the upper side of the boss merging with the flared upper end of the socket, the said socket and the said grooves being designed 95 to receive relatively angularly disposed portions of the said stem of the lamp.

In testimony whereof I affix my signature.

ELI ISRAEL. [L.S.]
